UNITED STATES PATENT OFFICE.

GEORGE F. EGAN, OF JERSEY CITY, NEW JERSEY.

DISPLAY DEVICE.

Original application filed August 3, 1925, Serial No. 47,865. Divided and this application filed November 28, 1927. Serial No. 236,299.

The present invention relates to improvements in display devices, and constitutes a division of my co-pending similarly entitled application, Serial No. 47,865, filed August 3, 1925.

An object of the invention is to provide an improved display device for holding display cards or tags.

Another object of the invention is to produce an inexpensive, simple and durable device by means of which a card or tag may be displayed on a surface, such as a counter, or by means of which a card or tag may be held upon a shelf without in any way encroaching upon the shelf space.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of a display device embodying my invention and indicated as fitted upon a shelf shown in dotted lines;

Figure 2 is an end view of the display device;

Figure 3 is a transverse section taken therethrough; and

Figure 4 is a front elevation with a card in place therein.

In the drawings, 68 and 69 indicate a pair of members. These members are adapted to engage upon opposite sides of a shelf, as 53, shown in dotted lines. These members are preferably made from the same piece of sheet metal and are shown as connected by

straps 70 and 71 of substantially V-shape and having their points extending toward one another. 73 designates a strap shown as extending across the upper front portion of the device just below the upper clamp 68.

This strap 73 is shown as offset outwardly of the plane passing through the two straps 70 and 71. A slot 72 is shown as provided between the forward edge of the clamp 68 and the strap 73 for the insertion of a card 27 shown in Figure 4. The card passes in

front of the straps 70 and 71 and rests at its lower end upon a ledge 74 formed in one piece with the forward edge of the lower

clamp 69 and bent outwardly and upwardly therefrom in offset relation to the plane of 55 the straps 70 and 71.

The card 27 may be inserted downwardly through the slot 72 passing in front of the straps 70 and 71, and be received at its lower edge within the ledge 74. The strap 73 holds the card 27 against falling forward and outward.

While I have shown the device in Figure 1 as held upon the shelf 53, it will be readily understood that the device may be placed on a counter or other like surface and there display a card. If it be desired to display a card at an angle on a counter it is only necessary to bend up the member 69 sufficiently to give the front of the device the 70 angle desired.

It is obvious that various changes and modifications may be made in the details of construction and design of the above specifically described embodiment of my invention 75 without departing from the spirit thereof, provided such changes fall within the scope of the following claims which define the invention.

What is claimed is:—

1. A display device comprising upper and lower members, end straps of substantially V-form connecting the end portions of said members, a strap extending longitudinally between the first mentioned straps and having a slot for receiving a card, and a ledge outwardly of the first mentioned straps and in alignment with said slot.

2. A display device made from a single piece of sheet metal comprising upper and lower members and straps connecting the end portions of said members, a longitudinal strap extending lengthwise between the upper portions of the first mentioned straps and offset outwardly of the plane passing through the first mentioned straps, said display device having a slot between the longitudinal strap and the upper member for receiving a card, and a ledge extending forwardly and upwardly from the lower member between the first mentioned straps for receiving and confining the lower edge of a card.

In testimony whereof I affix my signature.

GEORGE F. EGAN.
